SPACE VEHICLE

Joseph M. Denney, Palos Verdes, Calif., assignor to Space Technology Laboratories, Inc., Los Angeles, Calif., a corporation of Delaware

Filed Mar. 15, 1961, Ser. No. 64,306

Term of patent 14 years

(Cl. D71—1)

FIGURE 1 is a front perspective view of a space vehicle, showing my new design;

FIGURE 2 is a top elevation view thereof;

FIGURE 3 is a side elevation view thereof; and

FIGURE 4 is a bottom elevation view thereof.

I claim:

The ornamental design for a space vehicle, substantially as shown.
